Primary Examiner — Sheryl Lane*Assistant Examiner* — Samantha N Wood(74) *Attorney, Agent, or Firm* — Drinker Biddle & Reath LLP(57) **CLAIM**

I claim the ornamental design for an electronic musical instrument, as shown and described.

DESCRIPTION

FIG. 1 is an upper-right-front perspective view showing the design.

FIG. 2 is a front view thereof.

FIG. 3 is a rear view thereof.

FIG. 4 is a left-side view thereof.

FIG. 5 is a right-side view thereof.

FIG. 6 is a top view thereof; and,

FIG. 7 is a bottom view thereof.

The broken lines are included for the purpose of illustrating the environmental structure and form no part of the claimed design.

1 Claim, 7 Drawing Sheets(56)
